UNITED STATES PATENT OFFICE.

JOHN J. REDEKER AND HERBERT L. THOMPSON, OF ELGIN, ILLINOIS, ASSIGNORS TO
ELGIN GAS MOTOR COMPANY, OF ELGIN, ILLINOIS, A CORPORATION OF ILLINOIS.

MUFFLER.

1,304,096.

Specification of Letters Patent. Patented May 20, 1919.

Application filed April 15, 1918. Serial No. 228,581.

To all whom it may concern:

Be it known that we, JOHN J. REDEKER and HERBERT L. THOMPSON, citizens of the United States, residing at Elgin, in the county of Kane and State of Illinois, have invented certain new and useful Improvements in Mufflers, of which the following is a specification.

This invention relates to a muffler for an internal combustion engine, and the principal object is to provide a device of this kind which is made up of pressed sheet metal sections so that it will be light, simple and inexpensive in construction, but still will be effective and efficient in operation.

The invention consists in the novel construction, combination and arrangement of the parts.

In the accompanying drawing—

Figure 1 is a view mostly in section of a muffler constructed in accordance with the principles of this invention.

Figs. 2 and 3 are inside views of the two end pieces; and

Fig. 4 is a view of a portion of one of the sections of which the muffler is made up.

It is common practice to make mufflers of this kind of sheet metal and castings, but an outer casing is usually provided which covers the other parts, except the end pieces, and the present invention therefore is for a different construction in which the sections which make up the muffler are nested together so that their outer edges form the casing, the sections being held together between the end pieces by a suitable fastening device. The muffling or silencing effect and the capacity of the device can be varied by varying the number of intermediate sections.

The muffler being light and simple in construction is particularly designed and intended for use in connection with small gas engines, but of course may be made for engines of larger sizes.

In this muffler there are end pieces 1 and 2 with intermediate sections 3 and 4 arranged alternately between the end pieces. The end piece 1 is formed with an outer hollow tubular extension 5 threaded on the in-

side to receive a correspondingly threaded end of a pipe 6 which leads from the engine to which the muffler is attached. On the inside of this end plate are ribs 7 for supporting a central threaded hub 8 into which one end of a threaded rod 9 is screwed. The

other end plate 2 has a central rounded projection 10 on the outer side which merges into a hollow tubular projection 11 which forms a discharge for the muffler. The rounded projection 10 is formed with an unthreaded perforation 12 in its outer wall through which the opposite end of the rod 9 extends a sufficient distance to be engaged by a nut 13 for drawing the sections 3 and 4 together between the end plates.

These sections 3 and 4 are similar in the respect that they are both formed of sheet metal, and the outer edge of each one is bent or crimped in one direction to form a sort of a flat cup with a portion 14 of reduced diameter adjacent the flat or transverse portion thereof so that the edge of each section will engage and fit over the reduced portion 14 of the next one, thereby allowing them to fit tightly over each other forming a substantially flush outer surface, but spacing the transverse portions of the sections apart

so that they will not fit too tightly within each other, but will allow a considerable space for the circulation of the gas admitted to the muffler. The sections 3 have a large central perforation 15, and the sections 4 have a smaller perforation 16 through which the rod 9 may be inserted with some play to allow for inaccuracies, the perforation 15 of the sections 3 being sufficiently large to permit the whole volume of gas admitted through the tubular extension 5 without any restriction thereof. In the other sections 4 a number of tongues 17 are pressed outwardly from the bottom of the section forming perforations 18, and the tongues being only partially bent back in an inclined position, so that the gas in passing through the perforations 18 is given a kind of a whirling movement which further breaks up and diffuses the gas.

In order that the edges of the section adjacent the end piece 1 may fit properly over it, the edge is formed with an inclined portion 19 corresponding to the reduced portion 14 of the sections themselves, and when the sections are pressed together between the end plates, the one nearest to the end plate 1 is pressed firmly on the inclined portion 19 so that a substantially tight joint is made thereby. The other end plate 2 abuts the flat side of one of the sections 3, and it is unnecessary for the edge of this end piece to be shaped to receive the edges of the sections.

This end piece is therefore preferably made flat and slightly less in diameter than that of the adjacent section, the rounded portion 10 communicating freely with the interior 5 of the section 3 through its central opening 15.

In assembling the parts, the sections 3 and 4 are preferably arranged alternately with one of the sections 3 at each end and 10 they are clamped between the end plates 1 and 2, as described. The exhaust of the engine enters through the end piece 1 where it passes through the center of the sections 3 and is given a whirling movement through 15 the perforations nearer the periphery of the next section 4. This action is repeated until the exhaust escapes from the other end of the muffler through the tubular member 11 of the end piece 2. It is easy to take this 20 muffler apart for repair or for cleaning it,

and other sections can be added, substituted or removed by simply varying the length of the connecting rod 9.

We claim:—

In an exhaust muffler, a series of sheet 25 metal sections, and means to bind them together, the alternate sections being formed with a central perforation for the exhaust, and the intermediate ones each having tongues bent at an angle out of the section 30 on radial lines and at a distance from the center thereof so that the exhaust will be given a tangential whirling movement as it passes to the next section.

In testimony whereof we have signed our 35 names to this specification on this 8th day of April A. D. 1918.

JOHN J. REDEKER.
HERBERT L. THOMPSON.
